UNITED STATES PATENT OFFICE.

FREDERICK O. ROGERS, OF BOSTON, MASSACHUSETTS.

ELASTIC SPRING-COUPING.

SPECIFICATION forming part of Letters Patent No. 336,593, dated February 23, 1886.

Application filed September 9, 1885. Serial No. 176,642. (No model.)

To all whom it may concern:

Be it known that I, FREDERICK O. ROGERS, of Boston, in the county of Suffolk and State of Massachusetts, have invented a new and useful Improvement for Elastic Spring-Pack-
5 ing and Outer Connections or Coupling be-
tween the Upper and Lower Leaf-Springs of
Carriages, of which the following is a clear,
full, and exact description, reference being
10 had to the accompanying drawings, making
part of this specification, in which—

Figure 1 is a view representing a complete packing connection or coupling in section. Fig. 2 is a sectional view of the inside end of said packing-connection, and Fig. 3 is an outside sketch of the packing-box with the continuation of the outer ends of the upper and lower springs of the carriage.

My improved packing connection or coup-
20 ling of the upper and lower parts of a carriage-
spring consists of the packing-box F, made of
east-iron, brass, or other suitable material,
which is a solid shell forming the top, two
sides, and outside end, of which Fig. 1 repre-
25 sents a full-sized one for small carriage, with
one side left out to show the packing of the
ends of the upper and lower springs, A and B,
bent, the upper over the two bolts with the
two longer curves, a a, and the lower with the
30 two shorter curves, b b.

C represents the elastic inside packing be-
tween the upper and lower springs, made of
molded rubber or other suitable material
about five times as thick at the inside end to-
35 ward the carriage-body as at the other end
toward the carriage-wheel, and the full width
of the springs.

D represents the elastic inside packing on
top of the upper spring, A, and below the top
40 of the packing-box F, and E represents the
elastic inside packing under side of the lower
spring, B, both of which last-named elastic
packings are about three times as thick at
their outer ends as at their inner ends, and
45 are the full width of the springs.

G represents a steel or metal bearing under
the lower elastic packing, of full width of the
springs, and of the length of the inside of the
packing-box F, with the two shorter curves
therein over the two bolts h h, that pass through
50 the lower edge of the packing-box from side
to side to hold the springs and packings com-
pactly in their places, respectively. By this
arrangement a neat, compact, and strong coup-
ling of the springs is made that is water-proof
55 and very durable, and thereby, also, the elas-
ticity and strength of the springs themselves
are greatly increased by giving them each a
double-action leverage against the elastic
packings. The outer ends of the upper and
60 lower elastic packings, D and E, being made
thicker than their inside ends, enables them
to contract more as the loaded springs spread
apart at their outer ends, while at the same
time the middle elastic packing, C, being much
65 thicker at the inside end (toward the carriage-
body) than at its outer end, (toward the car-
riage-wheel,) enables it to contract more under
pressure of the springs when loaded.

In Fig. 1, A and B represent sections of
70 outer ends of elliptical springs, and in Fig. 3
A represents a section of the outer end of a
spring which is bent at right angles edgewise
at 4, passing under and fastened to the car-
riage-body by bolts or other suitable means.
75

What I claim as my invention and improve-
ment, and desire to secure by Letters Patent,
is—

The packing-box F, together with elastic
packings C, D, and E and the metal bearing
80 G, with curves in it and in the springs and
packings to match, all fastened compactly to-
gether by the bolts h h, constructed substan-
tially as shown and described, and for the pur-
poses set forth.

FREDERICK O. ROGERS.
